UNITED STATES PATENT OFFICE

138,568

DESIGN FOR A CONDIMENT DISPENSER, OR SIMILAR ARTICLE

Max L. Goldbert, New York, N. Y.

Application November 13, 1943, Serial No. 111,674

Term of patent 14 years

(Cl. D44—23)

To all whom it may concern:

Be it known that I, Max L. Goldbert, a citizen of the United States and a resident of the Borough of Manhattan, city, county and State of New York, have invented a new, original, and ornamental Design for Condiment Dispenser, or Similar Article, of which the following is a specification, reference being had to the accompanying drawing, forming a part thereof, in which:

Fig. 1 is a perspective view of a condiment dispenser, showing my new design;

Fig. 2 is a top plan view; and

Fig. 3 is a side elevational view thereof.

I claim:

The ornamental design for a condiment dispenser or similar article, as shown.

MAX L. GOLDBERT.
